WALL AND POST CONSTRUCTION

Conrad T. Hansen, Bywood, Pa., assignor, by
mesne assignments, to The E. F. Hauserman
Company, a corporation of Ohio

Application July 13, 1931, Serial No. 550,437

2 Claims. (Cl. 189—34)

My invention relates to wall and post construction and the like, being especially concerned with sheet metal partitioning and the like, and with the interconnection of its main structural components, such as panel sections or units, post members, horizontals and cornices. I aim to improve and strengthen the construction, and to reduce the time and cost of erection. How these and other advantages can be realized will appear from the description hereinafter of one form of sheet metal construction conveniently embodying the invention.

On the drawings, Fig. I is a fragmentary side view of a partition wall construction conveniently embodying my invention, portion being shown broken away and in section.

Fig. II is a similar view at right angles to Fig. I, with the panels omitted.

Fig. III shows the post or column of Figs. I and II in horizontal section, as indicated by the line and arrows III—III in Fig. II.

Fig. IV is a fragmentary plan view of the cornice and certain associated parts, illustrating the attachment of subjacent parts to the cornice.

Fig. V is a tilted view of the spacer and securing device shown in Figs. I—III.

Fig. VI is a tilted view of a plate with lugs for securing the ends of a horizontal member of the partition.

Fig. VII is a tilted view of a plate employed in the attachment of a subjacent member to the cornice; and,

Fig. VIII is a tilted view of a bracket employed for the same general purpose.

I have here illustrated my invention as applied to the type of partitioning shown in the application of Alvin C. Goddard, Serial No. 354,735, filed April 13, 1929, assigned to the assignee of this application, to which reference may be had for features not here more fully shown or described.

Structurally, the various parts forming the partition are held erect and in position by vertical uprights 9, 9 at the junctions of adjacent unit sections 10, 10. Fig. I shows portions of two such sections or panel units 10, 10, surmounted by a common cornice 11. The uprights 9, 9 are provided in pairs associated with the adjacent panel units 10, 10, and may be secured to the floor at their lower ends (not shown) in any suitable way. To close the interval between the uprights 9, 9 and conceal the parts within, there are channel-like cover plates 12, 12 (Figs. III and IV) removably mounted and secured as hereinafter described, and coacting with the uprights 9, 9 to

form an apparent post or column 13. In the present instance (as in the application above mentioned), each upright 9 forms part of the structural frame of its panel 10, being connected to the other similar upright (not shown) of said panel 10 by horizontals 14, 15, etc., whose ends may be fastened to the uprights as hereinafter described. In the openings of the frame formed by the members 9, 14, 15, etc., are mounted the individual panels 17, 18, etc., whose edges may be engaged with or secured to the members 9, 14, 15, etc., in any suitable manner.

As here shown (Fig. III), the uprights 9 are of generally channel section, with their webs 19 reversely grooved, and are arranged facing away from the panel units 10 to which they belong,—so that (and this is one important feature in relation to this invention) the individual panel unit 9 has marginal flanges 20, 20 extending side by side toward those of the adjacent unit 9, and (another important feature) the individual post 13 formed by the adjacent channel uprights 9, 9 is hollow. These features are, it may be remarked, in some degree independent; i. e., the panel unit 10 might be provided with marginal flanges 20 otherwise than by including in its construction a post-forming channel; and a hollow post 13 might be formed of cooperating channel uprights 9, 9 without their forming parts of panel units 10 as here shown. The main flanges 20, 20 may have inturned subflanges 21, 21 at their edges.

The panel units 10, 10 are spaced apart and interconnected, at suitable vertical intervals, by interposed spacers 22 housed in the post 13, and consisting of horizontal plates of suitable outline. On its opposite sides (edges), the spacer plate 22 has pairs of shoulders 23, 23 that engage between the edges 21, 21 of the adjacent flanges 20, 20, to space the panels 10, 10 apart. Adjacent the shoulders 23, 23, the plate 22 has other shoulders 25, 25 that engage the flange edges 21, 21 and align them with one another. At its other sides (edges) or ends, the spacer plate 22 has lateral downward extending hook lugs on tongues 26, 26; and the channel uprights 13, 13 have corresponding internal engagement means on their webs, consisting of sheet metal pockets or straps 27, 27 that may be formed by shearing the channel webs transversely and offsetting inward the metal adjacent (or between) the cuts. The upper (and lower) edges of the pockets or straps 27, 27 are flared to facilitate engagement of the tongues or lugs 26, 26 with them. As shown in Fig. I, the walls of the pockets 27 are embossed

to afford shoulders or ridges 28, and the lugs 26 have their lower ends embossed or turned inward toward one another at 29 to afford shoulders for locking under the ridges 28. Beyond its shoulders 23, 23 at each side, the spacer plate 22 has other shoulders 30, 30 which in effect form a head for engaging and securing the cover 12, these shoulders 30, 30 being formed by the curled ends of a downward-bent "head" portion 31 that 10 projects between the flanges 20, 20 and (as shown) also overlaps these flanges. As shown especially in Figs. III and IV, the spacer plate 22 has embossed reinforcing ridges 32, 33 that stiffen the bends of the laterally extending lugs 26, 15 26 and heads 31, 31,—the ridges 32 for the lugs 26 being on the upper and outer side of the plate and lugs, and the ridges 33 for the heads 31 on the lower and inner sides. The plate 22 also has a central opening 34 to afford passage for 20 wiring.

In erection, the panel units 10, 10 (or the post uprights 9, 9) are placed in position and secured to the floor, and then the spacers 22 are put in place. For this purpose, each spacer 22 is turned 25 vertical and inserted between adjacent flanges 20, 20, with its shoulders 23, 23 adjacent the latter; it is then turned horizontal, and its hook lugs 26, 26 are engaged in the pockets 27. It is then pressed or driven home until the tongue 30 ends on shoulders 29, 29 snap under the shoulders 28, 28,—the resiliency of the channels 13, 13 permitting them to yield inward after the flanges 28 are engaged against the shoulders 30,—so that the parts are tightly held. The driving 35 home of the spacers 22 completely aligns and spaces the panel units 10, 10 and the uprights 9, 9 horizontally, and also aligns them vertically,—notwithstanding any unevenness of the floor. The spacer 22 can be easily removed by a few 40 upward hammer taps on its lower side. After all the spacers 22 are in place, the covers 12, 12 can be easily applied and snapped over the shoulders 33, 30, by virtue of their own resiliency and the slight resiliency of the T-heads 31, 31. 45 Thus the adjacent panel units 10, 10 (and uprights 9, 9) are disengageably interconnected by the spacers 22 substantially in the mid-line of the partition.

As shown in Fig. I, the horizontals 14, 15 have 50 on their ends apertured tongues or lugs 36 projecting through openings in the web, and formed by portions of a plate 37 or 37a welded to each horizontal (Figs. I, II, and VI). As shown in Figs. I and II, the U-bent plate 37a is apertured 55 at 37b for the passage of wiring. These horizontal lugs 36 need not be interconnected by spacers 22, but may preferably be secured individually, as by wedge-keys 38 driven through them. This may be done at the factory, so that 60 the panel units 10, 10 can be shipped complete and ready for erection.

As shown in Figs. I, II, and IV, the cornice 11 is in cross-section a one-piece sheet metal trough,

with its bottom channelled or grooved longitudinally at 41. To secure the cornice 11 to the tops of the uprights 9, 9, the latter are provided with apertured tongues or lugs 42 at their ends, which project up through holes 43 in the cornice bottom to take wedge keys 44 driven through the lug apertures. The holes 43 are shown wide enough to permit some variation or shift in position of the lugs 42 and the member 9. As shown, a channelled and apertured saddle plate 45 (Figs. I, II, IV, and VII) is interposed between the keys 44 and the bottom of the cornice 11 to distribute the stresses to the latter at either side of the cornice groove or rib 41. The tongues or lugs 42 consist of portions of a plate 46 welded to the web 19 of the upright 13, and apertured at 47 (Fig. VIII) to take the lugs 36 of the horizontal 14,—so that this plate 46 helps to distribute the stresses to the web 19 of the upright 13. The upper portion 48 of the plate 46 is sheared from around the lugs 20 42 and bent over at right angles to the lugs, thus forming a bracket adapted to bear against the lower side of the cornice 11 and help receive the stress. This portion 48 is apertured at 49. It will be understood that in practice all four of the 25 keys 44 shown need not be used: e. g., two keys 44, one through a lug 42 on one upright 13 and the other through the diagonally opposite lug 42 on the companion upright 13, will make an 30 amply secure attachment. As shown in Figs. I and IV, the cornice bottom has a hole 50 to permit passage of wires down into the interior of the hollow post 13.

Holes 51 in the cornice bottom, 52 in the saddle plate 45, and 49 in the bracket ear 48 permit the 35 attachment of the cornice 11 to the uprights 13 to be made by means of screw bolts (not shown), instead of by the ears 42 and keys 44, if preferred. In this case, of course, the plate 45 would be reversed from the position shown, to align the hole 40 52 with the holes 51, 49.

Having thus described my invention, I claim:

1. The combination with an apertured cornice and a subjacent post and horizontal, of an apertured ear projecting upward from the post 45 through the cornice, an apertured ear projecting endwise from the horizontal through said post and its ear, and keys through said ears, securing the horizontal to the post and the post to the cornice.

2. In a partition wall construction, the combination with an apertured cornice of a subjacent post and panel units, the latter each including a horizontal, spacers engaged between and interconnecting said panel units within said post substantially in the midline of the partition, an apertured ear projecting upward from the post through the cornice, an apertured ear projecting endwise from the horizontal through the post and its ear, and keys through said ears securing the horizontal to the post and the post to the cornice.

CONRAD T. HANSEN.
